VACUUM BREAKER

Henry J. Luff, Cleveland Heights, Ohio, assignor
to Mary A. M. Luff, Cleveland Heights, Ohio

Application July 30, 1935, Serial No. 33,859

13 Claims. (Cl. 4—70)

This invention relates to vacuum breakers for plumbing applications. The purpose of such a breaker is to prevent back siphonage of waste water into the flush water supply line, such as might otherwise occur in an emergency occasioning a vacuum in the supply line. Such occurrence would obviously result in serious contamination of the fresh water supply as will be appreciated by one familiar with the art.

An object of the invention is to provide a device which may be added to an old installation, by insertion between the flush valve of the flush water supply line and the closet or like plumbing fixture served by the line under control of the valve. Another object is to provide a device for the purpose which shall be without moving parts and consequently entirely sure of operation.

The worst condition to be met by such a device, is one wherein there is overflow or otherwise abnormally high water level in the fixture, such as might be caused by stoppage in the waste line, coincident with a sudden high vacuum in the flush water supply line occurring during the flushing operation.

A further object of this invention is to provide that the device will function properly even under such extreme condition.

The exact nature of this invention together with further objects and advantages thereof will be apparent from the following description taken in connection with the accompanying drawings, in which Fig. 1 is a typical sectional elevation of an embodiment of the invention; Figs. 2 and 3 are transverse sections of the same, as respectively in the planes of lines 2—2 and 3—3 of Fig. 1, the sectional plane of Fig. 1 being indicated by the line 1—1 of Fig. 2; Fig. 4 is a conventionalized elevation partly in section, showing an assembly of parts illustrative of the use of the device; Figs. 5, 6, and 7 illustrate a modified form of the device, being views corresponding to Figs. 1, 2, and 3 respectively.

With reference now to Figs. 1 to 4 of the drawings, the vacuum breaker comprises a housing adapted for connection at its upper end with the flush water supply line A of the plumbing fixture and at its lower end for connection with the plumbing fixture itself, such as the closet B, Fig. 4. The breaker housing as here shown is assembled in three parts: a cover 1 arranged for threaded connection with the supply line A as illustrated, a pipe 2 adapted for connection with the plumbing fixture B, and an intermediate part 3 interconnecting the parts 1 and 2 in a rigid assembly, as by the threaded relations indicated in

Fig. 1. The part 3 is enlarged to provide a chamber 4 of substantial volume and comprising an enlargement of the flush water passage through the housing. The chamber 4 is vented to atmosphere by large openings provided in the cover member 1, as indicated at 1a, the cover member including an apron part 1b overhanging these vent openings.

Means are provided for dividing the passage through the housing into a main flush water passage and an auxiliary passage. Such means are here shown as a generally tubular member having a straight section 5 of somewhat smaller diameter than that of the pipe 2, thus providing a central main passage 6 with an auxiliary passage 7 disposed annularly thereabout and including the chamber 4. The member 5 is here shown as mounted by securement in a head 8 disposed at its upper end, having the perforations 9, and peripherally secured between the cover member 1 of the housing and the adjacent terminating part of the supply line A. The tubular means 5 is supported at its opposite and lower end, as here shown, by a member 10 threaded thereupon and perforate as at 11 and loosely fitting within the pipe 2. This member 10 if employed, has a downward taper as indicated in Fig. 1, the arrangement being such that the parts at the lower end of the tubular member may act with injector effect whereby a flushing stream within the main passage 6 will induce confluence in the auxiliary passage 7. A baffle member 12 shown as of conical form, may be provided on the tubular member to oppose reverse flow in the auxiliary passage. The member 10 being employed, and the baffle 12 being located thereadjacent as indicated, the openings 11 are preferably directed toward the interior of the baffle. This baffle interior may be vented as at 12a, and clearance is provided between this baffle and the part 2 of the housing to permit as much flow through the auxiliary passage 7 as is permitted by the openings 9 at the entrance to the auxiliary passage and the openings 11 adjacent the mouth of the passage.

It will be apparent that the tubular means described and particularly the tubular member 5 thereof, provides a straight through downwardly directed main passage for flushing water, about which is an auxiliary passage in bypass relation with the main passage having inlet communication with the flush water stream from the supply line by way of the openings 9, leading by way of the chamber 4 past the baffle 12 through the openings 11 and thereupon having return communication with the main passage 6, at the mouth 55

of the tubular member 5. Also it is to be noted that the chamber 4 of the auxiliary passage is amply vented to the atmosphere.

In service the installation of the device is so made that the mouth of the tubular member 5 is substantially above the overflow line of the fixture to be served. Operation will be as follows:

Provided the line A be supplied with flushing water at a high pressure and the waste line C be clear, normal conditions thus prevailing, opening of the flush valve D admits flush water under pressure to the vacuum breaker. A large part of this water travels straight through the breaker by way of the main passage 6. A part, however, enters the auxiliary passage by way of the openings 9 and is thereafter returned to the main passage by way of the openings 11. Such normal flushing flow is indicated by the solid arrows in Fig. 1. The level of liquid in the auxiliary passage may rise considerably during the flushing operation but the chamber 4 is of sufficient volume to take care of such water. The return of water from the auxiliary passage to the main passage is assisted by the described injector action at the lower end of the tubular member, so that rise in the chamber 4 is minimized. The chamber 4 being always open to atmosphere by way of the large vent openings 1a, a gravity head is effective upon water within the auxiliary passage to move this water in flushing direction.

Suppose now the flush valve D be opened with pressure in the supply line A but with overflow conditions in the fixture B. The high velocity in the main passage 6 with the consequent injector effect upon flow in the auxiliary passage will prevent any backing up of contaminating water from the fixture to the supply line.

Suppose now normal conditions to exist in the supply line A at the commencement of a flushing operation, but overflow conditions in the fixture, and that during such flushing operation a high vacuum suddenly occurs in the supply line. Inertia of the flushing stream within the main passage 6 will continue that stream in motion toward the fixture. Such motion will tend, by the described injector effect, to maintain flow in the auxiliary passage 7 toward the fixture. The atmospheric pressure only will exist within the chamber 4 because of the large area of the vent 1a relative to the combined areas of the openings 9. Consequently air will be drawn in through the vent openings 1a, into the chamber 4 and up into the line A through the openings 9, as indicated by the dotted arrows in Fig. 1. There will be no rise of water through the vacuum breaker, and the breaking in the vacuum as will occur substantially at the openings 9 as before.

Suppose finally overflow conditions in the fixture and a vacuum in the supply line A when the valve D is opened. The mouth of the tubular member 5 being above the overflow line of the fixture, no waste water is siphoned up into the supply line. Instead, the supply line simply draws in air through the vent 1a and openings 9 as indicated by the arrows in broken lines in Fig. 1.

The simplicity of design of the vacuum breaker device is to be observed. The device involves no moving parts. The tubular member 5 with all of its associated parts carried thereby, may be removed as a unit upon disconnection between the supply pipe and the housing of the device. The device comprises simply two units,

the housing unit and the partition unit which provides temporary separation of main and auxiliary flushing streams as described.

With reference now to the modification of Figs. 5 to 7, the housing unit parts include a pipe 5 22 and enlarged head part 23 forming a chamber 24 of substantial volume, there being vent openings 21a in the part 23 effective at the chamber 24.

Tubular means are disposed within the housing to provide a central main passage 26, and auxiliary passage 27 for flush water. The tubular means as here disclosed, comprises a rigid assembly of a head part 28, a mouth part 30 and a pipe part 25 threaded therebetween. The tubular means are supported by a flange 28a on the head part 28, the flange being peripherally secured between the member 23 of the housing and the supply pipe A as before. Openings 29 are disposed about the head part 28 and overhung by a mask 28b, the mask being so disposed that flush water flowing downwardly through the breaker, will by its inertia have little if any tendency to outflow through the openings 29. Preferably these openings are within the flange 25 part 21b of the part 23 as indicated, whereby outflow through the openings 29 would be baffled against splashing through the vent 21a. A flange 28c upon the head part 28 disposed within the chamber 24, masks the upper extremity of the straight part of the auxiliary passage 27 so that sudden or great upflow through this straight part would not cause splash out through the vent opening 21a. The member 30 of the tubular means loosely fits within the pipe member 22 of the housing, and has openings 31 permitting return flow of flush water from the auxiliary passage to the main stream.

The member 30 extends downwardly beyond the member 25 for the purpose of determining an elevation for the mouth of the pipe 25 above the overflow level of the fixture to be served. It is important for safety and code specifications that such distance be at least two inches; and if the part 30 be omitted there is a tendency, from ignorance, that the pipe 22 might be shortened in making the installation.

Functioning of the device in its modified form will obviously be generally as in the form illustrated in Figs. 1 to 4 and heretofore described. The principal difference will be that in this modification little if any of the flush water will pass down through the auxiliary passage, such amount always depending upon conditions of pressure differentials, and the modified form being preferable for low water supply pressures.

The vent openings 21a extending straight through the wall of the housing enclosing the chamber 24, these openings are open for inspection and accessible for cleaning. Yet they are preferably small enough as illustrated, to prevent tampering with the interior parts or the loss of small articles which might otherwise fall into the chamber 24.

What I claim is:

1. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication with the flush water stream at an elevated location, and having return communication with

said main passage at a lower elevation, said breaker having an air vent communicating with said auxiliary passage at an elevation substantially above said return communication.

5 2. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication with the flush water stream at an elevated location, and having return communication with said 10 main passage at a lower elevation, said breaker having an air vent communicating with said auxiliary passage at an elevation substantially above said return communication, said auxiliary passage including an enlarged cavity elevated 15 above said return and communicating with atmosphere by way of said vent.

15 3. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication 20 with the flush water stream at an elevated location, and having return communication with said main passage at a lower elevation, said breaker having an air vent communicating with said auxiliary passage at an elevation substantially 25 above said auxiliary passage return and the parts being so proportioned and arranged that a flushing stream in one of said passages will tend to effect confluence in the other passage during the flushing operation.

30 4. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication with the flush water stream at an elevated location, and having return communication with said 35 main passage at a lower elevation, said breaker having an air vent communicating with said auxiliary passage at an elevation substantially above said auxiliary passage return, the parts adjacent said return being disposed to provide 40 injector effect to cause a flushing stream in one of said passages to induce confluence in the other passage.

45 5. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication with the flush water stream at an elevated location, and having return communication with said main passage at a lower elevation, said breaker having an air vent communicating with said auxiliary passage at an elevation substantially above said auxiliary passage return, the parts adjacent said return being disposed to provide injector effect to cause a flushing stream in said main passage to induce confluence in said auxiliary passage.

5 6. A vacuum breaker adapted to be disposed in the flush water supply line of a closet or like plumbing fixture, between the fixture and its flush valve in said line, said breaker having a main through passage for flushing water and an auxiliary passage for said water, in bypass relation with a section of said main passage, said auxiliary passage having inlet communication with the flush water stream at an elevated location, and having return communication with said main passage at a lower elevation, said breaker having an air vent communicating with said auxiliary passage at an elevation substantially above said return and said breaker having its parts adjacent said return disposed to provide injector effect to cause a flushing stream in one of said passages to induce confluence in the other passage, said auxiliary passage including an enlarged cavity elevated above said return and communicating with atmosphere by way of said vent.

15 7. A vacuum breaker adapted to be disposed in the flush water supply line of a closet or like plumbing fixture, between the fixture and its flush valve in said line, said breaker having a straight downwardly directed main passage for flushing water, and an auxiliary passage for said water annularly disposed about said main passage, in bypass relation with a section of the latter, said auxiliary passage having inlet communication with the flush water stream at an elevated location, and having return communication with said main passage at a substantially lower elevation, said breaker having air vent means communicating with said auxiliary passage at an elevation substantially above said return, the parts of said breaker adjacent said return being disposed to provide means effective to oppose reverse flow in either of said passages during flushing flow through the other.

30 8. A vacuum breaker adapted to be disposed in the flush water supply line of a closet or like plumbing fixture, between the fixture and its flush valve in said line, said breaker having a downwardly directed through passage for flushing water and generally tubular means disposed in said passage to divide the latter into a central main passage and an auxiliary passage thereabout and in bypass relation with said main passage, said auxiliary passage having inlet connection with the flush water stream adjacent the upper end of said tubular means and a return connection leading to said main passage adjacent the lower end of said tubular means, said breaker having air vent means communicating with said auxiliary passage at an elevation substantially above said return connection.

35 9. A vacuum breaker adapted to be disposed in the flush water supply line of a closet or like plumbing fixture, between the fixture and its flush valve in said line, said breaker having a downwardly directed through passage for flushing water and generally tubular means disposed in said passage to divide the latter into a central main passage and an auxiliary passage thereabout and in bypass relation with said main passage, said auxiliary passage having inlet connection with the flush water stream adjacent the upper end of said tubular means and a return connection leading to said main passage adjacent the lower end of said tubular means, said breaker having air vent means communicating with said auxiliary passage at an elevation substantially above said return connection, and said tubular means having its lower end part arranged

to provide injector effect to cause flushing flow in said main passage to induce confluence in said auxiliary passage.

10. A vacuum breaker adapted to be disposed in 5 the flush water supply line of a closet or like plumbing fixture, between the fixture and its flush valve in said line, said breaker having a downwardly directed through passage for flushing water and generally tubular means disposed in 10 said passage to divide the latter into a central main passage and an auxiliary passage thereabout and in bypass relation with said main passage, said auxiliary passage having inlet connection with the flush water stream adjacent the 15 upper end of said tubular means and a return connection leading to said main passage adjacent the lower end of said tubular means, said breaker having air vent means communicating with said auxiliary passage at an elevation substantially 20 above said return connection, and said tubular means having baffle means arranged to oppose reverse flow in said auxiliary passage.

11. A vacuum breaker adapted to be disposed in 25 the flush water supply line of a closet or like plumbing fixture, between the fixture and its flush valve in said line, said breaker comprising a housing having a downwardly directed through passage for flushing water and generally tubular means disposed in said passage to divide the latter into a central main passage and an auxiliary passage thereabout and in bypass relation with said main passage, said tubular means having a perforate head adjacent its upper end peripherally secured in said housing and being mounted for 30 upward removal from the housing upon release of said head, said auxiliary passage having connection with the flush water stream by way of the perforations in said head, said breaker housing having air vent means communicating with said 35 auxiliary passage at an elevation substantially 40 above said return connection, and said tubular

means having its lower end proportioned and arranged to be cooperative with said housing to cause flushing flow in said main passage to induce confluence in said auxiliary passage.

12. A vacuum breaker adapted to be disposed 5 in the flush water supply line of a closet or like plumbing fixture, between the fixture and its flush valve in said line, said breaker having a main through passage for flushing water and an auxiliary passage for said water, in bypass relation 10 with a section of said main passage, said auxiliary passage having inlet communication with the flush water stream at an elevated location, and having return communication with said main passage at an elevation lower than that of said 15 inlet but substantially above the overflow line of said fixture, said breaker having an air vent communicating with said auxiliary passage at an elevation substantially above said return communication. 20

13. A vacuum breaker adapted to be positioned 25 in the flush water supply line of a closet or like plumbing fixture, between the fixture and its flush valve in said line, said breaker having a downwardly directed through passage for flush- 30 water and generally tubular means disposed in said passage to divide the latter into a central main passage and an auxiliary passage thereabout and in bypass relation with said main passage, said auxiliary passage having inlet connection with the flush water stream adjacent the upper end of said tubular means, and having a return connection adjacent the lower end of said tubular means, said return connection 35 being located substantially above the overflow line of said fixture, said breaker having air vent means communicating with said auxiliary passage at an elevation substantially above said return connection. 40

HENRY J. LUUFF.
